UNITED STATES PATENT OFFICE.

JACOB KRITCH, OF CLEVELAND, OHIO.

RAILWAY-AXLE JOURNAL-BEARING.

SPECIFICATION forming part of Letters Patent No. 352,876, dated November 16, 1886.

Application filed August 21, 1886. Serial No. 211,520. (No model.)

To all whom it may concern:

Be it known that I, JACOB KRITCH, of Cleveland, in the county of Cuyahoga and State of Ohio, have invented a certain new and Improved Railway-Car Journal Box or Bearing, (technically known as "brasses,") the nature of which consists of a box having its journal-bearing surface composed of a compound or amalgam of metals suitable for said purpose, and the back or top thereof formed of cast-iron or its equivalent, in contact therewith by the force of adhesion, the said journal-bearing being made by casting, as hereinafter described.

For a more full and complete description of the said invention reference will be had to the following specification and to the annexed drawings, making part of the same, in which like letters designate like parts.

It is well understood by those skilled in the art of making and using railway-axle journal-bearings for railway-cars that, owing to the great pressure, strain, and thrust to which they are more or less subjected, they often crack or break to such a degree as to render them not only unfit for use, but also dangerous and resultant in serious accidents.

It is the purpose of this improvement to make the journal-bearings (or brasses) with a re-enforced backing or top of cast-iron or its equivalent, to prevent this destruction of the bearings and its results before mentioned.

Figure 1 is a perspective view of a railway-car-axle journal-bearing. Fig. 2 is a transverse section, and Fig. 3 is a longitudinal vertical section.

The drawings represent a special form of a journal-bearing. The improvement is, however, applicable to other forms of axle-bearings without departing from the nature of said invention.

In the drawings, A, Fig. 1, represents the journal-bearing as an entirety, B being the bearing-surface for the axle, and made of a compound or amalgam of metals suitable for the purpose designed, preferably composed of tin, one part, copper seven parts, and one-sixty-fourth part of phosphorus, which are combined by melting together, and form that part of the bearing indicated at C below the line D. The part above the line D or top EG is of cast-iron or its equivalent. At the end is a segmental

shoulder, F. Above and back of the collar is a flange, G, Figs. 1 and 2. The sides at H H are shaped for adaptation to a certain construction of housing or pedestals of the cars, which sides may be changed according to the nature of the case. The purpose of shaping the sides H H and flange G as shown is for adapting and holding the bearing in the housing and in relation to the axle. The segmental shoulder F is to prevent the bearing of the collar, by the lateral force of the axle, from cutting into the face B of the journal-bearing.

The ordinary axle-journal bearings (or brasses) become cracked, broken, or split usually in the radii of its center and longitudinally, owing to the vertical and longitudinal strain and thrust of the train. At times the bearing spreads away from the journal in the line a a, Fig. 2, so that only about the upper part, at c c, will be upon the axle-journal. In this way the bearing is either soon worn through, split, or cracked in two, and the journal cut thereby. This is especially the case in first using new bearings, which are so liable to become a "hot box." In this condition the result is that the bearing will more readily spread from the journal, leaving only a portion of the bearing for the journal, which is soon cut through or broken. By re-enforcing the bearing (or brass) by a backing of cast-iron this spreading of the bearing is effectually prevented, as the re-enforcing metal E is of such rigid tenacious character as to resist the more pliable and yielding nature of the compound metal part C of the bearing.

The two physical conditions of the metallic parts C and E are such that while the former is susceptible of more or less pliable extension and abrasion in its relation to the axle-journal the cast-iron backing, conversely to this, resists tensile strain in all directions in its adhesion to the section or part C, also resistant to the crushing-weight.

The described journal-bearing is made by casting in a mold of the article an alloy or compound of metals, as before described, or the equivalents thereof, and while in its heated state to pour into the same mold molten cast-iron or its equivalent, which in contraction with the said compound forms a rigid and durable adhesion therewith.

When a new bearing is used on a worn axle-journal, it is advisable to line the face of the bearing with Babbitt metal I, Figs. 2 and 3, for the purpose of reducing the frictional contact of the new bearing with the old journal, thereby finding its proper seat in the bearing.

I claim as my invention—

1. A journal box or brass consisting of a brass or bronze base having a journal-receiving recess therein and a cast-iron re-enforce backing upon the base, the whole of said re-enforce being above the journal-recess of the base and cohesively connected thereto, forming one integral body, substantially as described.

2. A journal box or brass consisting of a brass or bronze base having a journal-receiving recess therein and a re-enforce backing of cast-iron upon the base, the whole of said re-enforce being above the journal-recess of the base and cohesively connected thereto upon substantially a straight line, as and for the purpose set forth.

In testimony whereof I affix my signature in presence of two witnesses.

JACOB KRITCH.
